TALKING MACHINE

Walter Weigel, Chemnitz, Germany

Application July 8, 1933, Serial No. 679,531
In Germany April 26, 1928

3 Claims. (Cl. 274—1)

This invention relates to a phonograph provided with a device for automatically effecting the turning of a record played on one side to the extent of 180° and for returning the turned record 5 to the turntable.

Compared with known phonographs fitted with a device for attaining the same objects, the phonograph according to the invention differs in so far as its record gripper comprises two clamping jaws 10 or arms arranged on a shaft which is disposed on the bracket for the jaws and terminates at a small bevel gear in mesh with a larger bevel gear secured, with a ratchet wheel, to a bolt. This ratchet wheel is engaged by a pawl which by 15 means of rods actuated by an eccentric turns the clamping jaws 180°, and a collar provided on the gripper shaft and having flattened portions against which a leaf spring abuts arrests the clamping jaws in their normal or swung-out position involving a turn of 180°.

By way of example, the invention is illustrated in the accompanying drawings, in which Figure 1 is a top view of a talking machine of the magazine type; Fig. 2, a sectional side view of the record gripping mechanism; Fig. 3, a front view thereof; Fig. 4, a view of the locking device for the gripper arms; Fig. 5, a top view of a gripper arm; Fig. 6, a partial side view of the actuating device for opening and closing the gripper arms; Fig. 7, a top view on a larger scale of the device shown in Fig. 6; Fig. 8, a side view of the device shown in Fig. 7; and Fig. 9 shows the bell crank rods actuated by an eccentric.

Referring to the drawings, under the turntable 1 for the record 9 a worm wheel gear, not shown, is arranged which causes slow motion of a shaft 2 disposed in bearings 3. The shaft 2 carries the eccentrics 4 and 8 provided with lifting cams, and above the eccentrics lever arms 11 fitted with noses 10 are arranged in the bearings 12 as shown in Figs. 1 and 9. Each lever arm 11 is connected with a tension spring 13 and thus continually resting on the respective eccentrics 4 and 8. Each lever arm 11 is further connected with the rods 14, 15, 16, 17, 18, each of the rods being connected with a toggle 19. The rods 26 moved by the eccentrics 4, 5, 6, 7, 8 actuates a gripper which will be described below in such a way that the gripper will take a record 9 from the magazine 20, place it on the turntable 1, raise it about 45° after playing, turn it, put it on the turntable again and return it to the magazine 20 after the other side has been played also.

The gripper consists of two superposed clamping jaws 21 which are slightly bent towards their

ends, as indicated in Fig. 3, and are firmly connected with the hollow bolts 22, 23 displaceably guided in bearings 25, 26 screwed onto the plate 24. In the bolts at 29 bent levers 27, 28 are rotatably disposed which possess the rollers 30, 31, 30' and 31'. To insure perfectly vertical guiding of the hollow bolts 2, 23, a continuous bolt 32 is inserted therein. To the plate 24 vertically superposed angle pieces 33, 34 are firmly secured, and the bolts 22, 23 are also guided through these angle pieces 33, 34 and arranged so that they are in continual contact with the angle pieces 33, 34 and the rollers 30', 31' disposed in the bent levers 27, 28 when the grippers are closed. The clamping jaws 21 are pressed together by the compression springs 36 disposed on the bolts 35. The member 24 is firmly disposed on the shaft 37 rotatably disposed in the oval recessed arm 38 and connected with a bevel gear 39 which meshes with the bevel gear 40 which is twice as large as the gear 39. The gear 40 is connected by the bolt 41 with a ratchet wheel 42, as indicated in Figs. 7 and 8, which is engaged by the pawl 43. In front of the plate 24 on the shaft 37 a collar 44 is disposed which possesses the parallel faces 45, as shown in Fig. 4, and on one of these faces a leaf spring 46 presses continually which by a support 47 is attached to the gripper arm 38 movably disposed on the shaft 55 in the arms 56 which surround a hollow shaft 53 rotatably disposed in a bracket 58 on a base plate 57.

According to Figs. 2, 6 and 8, above the rollers 31 a double-armed lever 49, 50 is disposed on the arms 48 in such a way that a tongue 51 connected with the arm 50 slightly rests on the rollers 31, 35 as shown in Fig. 2. The arms 48 are connected with a ring 52 disposed on a hollow shaft 53.

On the lower portion of the hollow shaft 53 two interconnected and oppositely disposed arms 60, 61 are arranged which are articulated to the rods 40, 41, 45 connecting one of the elbow levers 19 with the eccentrics 4 or 5.

The rods 16, 17, 18 connected with the eccentrics 6, 7, and 8 are articulated to the toggles 16', 17', 18' suspended from the bearing 64 and 45 connected with the rods 16'', 17'', 18'' passing into the hollow shaft 53.

The rod 17'' is connected by the hollow shaft 53 with the double-armed lever 49, 50 and by the lever 65. The rod 18 is actuated by the eccentric 8 and acts on the rod 18'' which is connected with the carrier 66 on the arms 56 and with the toggles 67, 67' disposed in the carrier 66. From the boss 68 of the toggle 67' a rod 69 leads to a finger 70 which is firmly disposed on the shaft 55 to 55

which the gripper arm 38 is firmly connected also. The rod 16" actuated by the eccentric 6 is connected by the hollow shaft 53 with the lever 80 arranged in the carrier 66 on the bearing 56. The lever 80 is connected with the rod 81 connected with the pivot 73 of the finger 74 firmly connected with the bolt 41. The pivot 73 is connected with the pawl 43 which engages the ratchet wheel 42.

10 The hollow shaft 53 has cast-on flanges 75 for the set screws 75' which strike the stop 76 in the bracket 58 when the gripper is swung in and out.

The device functions as follows:

15 Prior to playing the jaws 21 acting as gripper arms are in the position shown in Fig. 1, whereupon the eccentric 7 begins to act by pressing down, by means of the rods 17, 17', 17", 65, the tongue 51 attached to the double-armed lever 49, 50, which in turn presses on the roller 31 of the bent lever 28. The roller 31' is thus pressed against the immovable angle piece 34 and the bolts 23 firmly connected with the lower jaw 21 are drawn down in vertical direction, so that the 25 gripper arms 21 are opened. In this open position the entire gripper moves in the direction of the arrow A in Fig. 1 prior to moving towards the record magazine 20 and picking up a record. For this purpose the eccentric 5 is provided which 30 acts on the rod 15 (arrow B in Fig. 7) so that the rod 15 drives the arm 60 and the hollow shaft 53 to which the arm 60 is firmly connected is displaced in the bracket 58. The hollow shaft 53 moves also the arms 56, the gripper arm 38 and thus the clamping jaws 21 in horizontal direction.

When the gripper has been swung out sufficiently and is adjusted so that it can grip a record, the eccentric 7 will release the tongue 51 and 40 the lower clamping jaw 21 will move vertically up while the lower compression springs 36 clamp the record 9 between the jaws 21. This clamping of the record is made quite effective owing to the fact that the jaws 21 have inwardly bent 45 ends. In this way cushioning is provided on both sides and the record is particularly firmly gripped by the ends of the gripper.

Then the eccentric 4 will draw the lever arm 61 by the rod 14 in the direction of the arrow C 50 and turn the hollow shaft 53, the gripper arm 38 and the jaws 21 with the record 9 back until the central aperture in the record will be exactly above the pin 76 in the turntable 1, whereupon the eccentric 7 begins to act and the tongue 51 causes the release of the record 9 from the 55 clamping jaws. The record lies then freely on the rotating turntable 1 and is driven in the customary manner while the tone arm, not shown, puts its needle on the record and after the record 60 has been played on one side is returned again to its initial position outside the record.

The record 9 is then caught again by the gripper arms 21 and the arm 38 together with the record 9 is turned 180° after the record has previously been lifted about 45°. For this purpose the eccentric 8 acts on the rod 18 (Fig. 8), moves the toggle 18' and draws the rod 18" vertically down. This motion is transmitted to the levers 67 and 67', the rod 69 and the lever 70 firmly 70 connected with the shaft 55. The lever 70 is moved in the direction of the arrow E in Fig. 8 and thus lifts the arm 38, which rotates in the bearings 56, and also the entire gripper with the record to the extent of 45°. In this position the 75 gripper remains for a time before the eccentric

6 acts on the rod 16 to move the elbow lever 16' which draws down the rod 16" in vertical direction. The rod 16" engages the elbow lever 80, 81 and moves the rod 81 in the direction of the arrow E in Fig. 8, so that the pawl 43 articulated to the rod 81 engages the next tooth of the ratchet wheel 42 which is moved about one-fourth of a circle. The ratchet wheel 42 is firmly connected by the shaft 41 with the large bevel wheel 40 which is thus also turned to the same extent. The wheel 40 transmits this motion to the bevel gear 39 which has half the size of the gear 40 and is therefore turned 180° like the gripper 21 with the record 9. As soon as the record has been turned 180°, the spring 46 rests tightly on one of the surfaces 45 on the collar 44 and arrests the gripper and record in horizontal position.

The record 9 is then placed on the turntable 1 and the lever 70 and the parts 69, 67', 67, 18" and 18 move in opposite direction to the direction indicated by the arrow E in Fig. 8 whereupon the gripper arm 38, the gripper device and the record 9 are slowly lowered into horizontal position in such a way that the central aperture of the record is placed accurately above the pin 76 of the turntable 1.

Then the gripper or the lower jaw thereof is opened in the manner described and the tone arm, not shown, swung into playing position for playing the back of the record. When this side has been played also, the membrane or diaphragm of the tone arm, both of which are not shown, is removed from the record and the tone arm moves away to such an extent that the needle of the diaphragm is disposed above the idle grooves of the record. At this moment the record is gripped by the jaws 21, and the entire gripping device moves again in the direction of the arrow A and conveys the record 9 into the magazine, the motion of the gripping device in the direction A taking place in the manner described. When the record has been placed in one of the compartments of the magazine 20, the jaws of the gripping device will open and the latter move quickly back into the position shown in Fig. 1.

I claim:—

1. A phonograph, in which the records are engaged by a gripper to be turned 180° and released again by the gripper after such a motion, comprising a turntable, a pair of superposed gripper arms for lifting a record from the turntable and reversing it, a bracket for said gripper arms, a shaft disposed in said bracket, a bevel gear connected with the end of said shaft, a bevel gear of larger size than said first bevel gear and in mesh therewith, a ratchet wheel for said second bevel gear, a bolt on which said second bevel gear and ratchet wheel are secured, a pawl engaging said ratchet wheel, rods actuated by an eccentric for swinging the gripper arms in a predetermined degree, a collar having flattened parts provided on said shaft, and a leaf spring engaging said flattened parts for locking the gripper arms in their normal and swung-out position involving a turn of 180°.

2. A phonograph according to claim 1, wherein the superposed gripper arms are under spring pressure, and comprising bolts firmly connected with the arms and displaceably guided in a plate secured to the shaft carrying the smaller bevel gear, angle pieces secured to said plate, said angle pieces being penetrated by the outer ends of said bolts forming each a bearing for a bent lever,

one end of one of said levers being within range of a tongue connected by rods with a cam, the other end of said lever influenced by said tongue being connected with a roller and positioned within range of one of said angle pieces to draw down the bolt connected with the lower one of said superposed gripper arms to open the gripper.

3. A phonograph according to claim 1, wherein the superposed gripper arms are under spring pressure, and comprising hollow bolts firmly connected with the arms and displaceably guided in a plate secured to the shaft carrying the smaller bevel gear, a continuous rigid bolt within said

hollow bolts to insure perfectly vertical guiding thereof, angle pieces secured to said plate, said angle pieces being penetrated by the outer ends of said bolts forming each a bearing for a bent lever, one end of one of said levers being within range of a tongue connected by rods with a cam, the other end of said lever influenced by said tongue being connected with a roller and positioned within range of one of said angle pieces to draw down the bolt connected with the lower one of said superposed gripper arms to open the gripper.

WALTER WEIGEL.
